UNITED STATES PATENT OFFICE.

SEYMOUR W. BONSALL, OF NEW YORK, N. Y.

WARDROBE OR SHOW-CASE.

SPECIFICATION forming part of Letters Patent No. 760,726, dated May 24, 1904.

Application filed February 18, 1904. Serial No. 194,305. (No model.)

To all whom it may concern:

Be it known that I, SEYMOUR W. BONSALL, a citizen of the United States, residing in the city, county, and State of New York, have 5 invented a certain new and useful Improvement in Wardrobes or Show-Cases, of which the following is a specification.

This improvement has particular relation to 10 means whereby certain forms of closets and wardrobes are made convenient and available for the suspension of various articles, and particularly of garments and the like, while permitting such easy access and full inspection as would otherwise not be possible.

15 The improvement is applicable in some of its forms to use in wardrobe-trunks, showcases, and similar devices.

This improvement is particularly useful in 20 making convenient and available for the suspension of various articles those spaces which would otherwise be so low as to be unsuited to this purpose. Where a closet is so low that a man or woman is obliged to lean over in 25 order to look into it, it is not convenient for the suspension of garments and the like on account of the difficulty in picking out the particular clothing desired at any time and because the user must either stoop down in 30 order to see the hooks or must grope about for the hook required.

In my United States Patent No. 642,075 I have shown a device applicable to any closet, which permits the clothing to be drawn forward into sight when any particular garment 35 is desired and also facilitates the hanging up and inclosing of garments in a manner to preserve the desired folds and prevent mussing. This device is particularly suitable to deep and narrow closets for wardrobes, but is not 40 so useful in connection with wide and shallow closets.

The present improvement will be found particularly advantageous in those spaces which are otherwise too low for convenient suspension of the garments and are too shallow and wide to develop the full convenience of the device described in my aforesaid Letters Patent. There are many instances where a space 45 of this kind can be very conveniently combined with a sideboard or bureau, with or with-

5 out a mirror above the space in question, and hitherto such spaces have not been capable of employment for hanging garments conveniently.

The present improvement is applicable not 55 only in the particular cases above set out, but in many other localities where other forms of suspending means are not convenient.

This improvement is illustrated in a preferred form employed for hanging garments 60 in the accompanying drawings, wherein—

Figure 1 is a perspective view of a closet or wardrobe opened, so as to show my improved apparatus. Fig. 2 is a vertical median section of the same with doors removed, 65 and Fig. 3 is a sectional view of certain details.

Any convenient form of wardrobe or closet is shown at 1, the same being preferably provided with a door or doors 2, which may be 70 of any desired character. In my Letters Patent above named the garments are shown hung with their width at right angles to the direction in which they can be slid in and out of the closet; but the present improvement involves the use of a hanger-support so placed 75 that the garments can be drawn out of the wardrobe in the direction of their greatest width.

In the drawings the garments are shown at 80 3 in Fig. 2 suspended upon hangers shown at 4 in Fig. 1, which hangers are provided with hooks resting upon the immediate hanger-support 5, which takes the form of a horizontal rod on which said hooks can slide and 85 from which they can be easily removed. The hanger-support 5 is carried by a tilting frame, which preferably comprises a base-board 6 at one or both sides of the closet or wardrobe 1 and appropriate bracing means which 90 complete the frame. In the specific form shown two base-boards 6 are employed, connected by the horizontal braces 7 and the diagonal braces 8. The tilting frame which carries the hanger-support 5 is pivoted at 95 both sides, and said frame preferably occupies the entire width of the wardrobe.

In Fig. 3 there is shown the preferred pivotal means whereby the base-boards 6 are attached to their supports. The base-plate 9 100

is fixed to the inside of the wardrobe 1 and is provided with a sleeve 10 near its center, through which the securing-pin 11 projects. This pin is preferably provided with a screw-thread at its outer extremity and shaped with a retaining-head which can be embedded in the side of the wardrobe, which is shown in the figure. The lower end of the base-board 6 is perforated and fits over the sleeve 10, being provided with a large washer 12 around the perforation on which it is pivoted. The butterfly-nut 13 serves to secure the base-board in place by being screwed onto the end of the pin 11.

15 The principal use of the base-board 6 is to prevent the clothing or garments carried by the hangers 4 from rubbing on the side of the wardrobe or against the door or doors when the frame is tilted backward or forward. 20 The base-board 6 can be further utilized as a flat abutment against which the garments can be pressed firmly by any desired means—as, for instance, by the presser-bar 14, shown in the drawings, which is employed in the manner set forth in my Letters Patent No. 661,947.

25 The arrangement so far described is particularly suitable to those closets which are not much more than deep enough to accommodate the width of the clothing and are at 30 the same time wide enough to permit a large number of garments to be placed flat one on the other from side to side of the closet.

In any form of closet, however, and whatever the form of hangers used this device 35 will be found most useful when for any reason it is not convenient to enter or look into the space where the garments are hung. In such a case access is very easily had to all the garments at once by using the device 40 shown in the drawings. It is only necessary to draw the tilting frame forward until the hangers are brought far enough in front of the edge of the closet to bring the garments into easy view and reach. When in this position, the projection 15 on the frame comes 45 in contact with the fixed stop 16, and the whole frame is then secured from any tendency to fall forward.

It is to be observed that the pivots of the 50 tilting frame are best placed about half-way between a vertical plane through the rod 5 in the extreme backward position (shown in Fig. 2) and a similar plane through said rod when drawn into its extreme forward position. 55 (Shown in Fig. 1 and indicated in dotted lines in Fig. 2.) By adopting this arrangement the level of the rod is the same in both extreme positions, and the weight of the whole tilting frame and of the garments carried thereby 60 tends to preserve each extreme position into

which the frame is brought—that is to say, gravity tends to press the back of the frame against the back of the closet or other support which may be provided for it when in the position shown in Fig. 2, and the same 65 effect will be produced when the frame is tilted forward until the projection 15 strikes the stop 16. By making the distance sufficient between the hanger-support 5 and the pivotal line of the tilting frame the lift of 70 the hanger-support 5 during passage back or forth may be made as small as desired, thus making the effort required to move the frame very slight.

It will be seen that while garments may be 75 normally kept pressed in proper folds against the base-board by means of the bar 14 it is easy to disengage them when the tilting frame is drawn forward and in that position to remove any one garment which is then clearly 80 in view without any of the others.

It is to be understood that while I have shown in the drawings an apparatus fastened to the sides of the closet or receptacle this invention covers a device of the character 85 claimed however mounted and wherever fastened within such receptacle.

A variety of changes may be made in this invention without departing from the spirit and scope of the same, and I am not to be understood as limiting myself to the details herein shown and described.

What I claim is—

1. In a device of the class described, a receptacle, a tilting frame pivoted within the 95 same near the forward bottom edge thereof, and comprising two sides and bracing means at the rear, a hanger-support carried upon said frame and extending at right angles to its direction of movement, hangers suspended 100 crosswise of said hanger-support and a stop placed so as to limit forward movement of the frame when the hangers are brought into view in front of the receptacle; substantially as described.

2. In a device of the class described, a receptacle, a tilting frame pivoted therein, and comprising a flat base-board against one side of the receptacle, a horizontal hanger-support fixed to said base-board at right angles thereto, hangers suspended crosswise of said hanger-support and a stop limiting movement forward when the hangers are brought into view in front of the receptacle; substantially as described.

SEYMOUR W. BONSALL.
